ELECTRIC PULL CHAIN SOCKET

Harmon J. Cook, Torrington, Conn.

Application January 27, 1931, Serial No. 511,523

11 Claims. (Cl. 173—354)

This invention relates to electric switches and circuit breakers, and more particularly to an electric pull chain socket switch of the "hill and valley" type, which will be capable of carrying and interrupting quite heavy loads without danger of injurious arcing or flash-overs.

One object is to provide a pull chain socket switch of the intermittently operated ratchet type, in which the rotary contact carrier will be telescopied within the stationary contact base whenever the switch is in the fully open or fully closed position.

A further object is to provide a pull chain socket switch of the above nature, in which the rotary contact carrier is provided with a pair of downwardly projecting inclined lugs for supporting the two sides of the rotary contact, said lugs being adapted to snap below the upper surface of the stationary contact base for filling the space surrounding the contacts.

A further object is to provide a pull chain socket switch of the above nature in which any arc which may be started by the separation of the contacts will be instantly checked and destroyed by the interposition of an insulating barrier between said contacts which blots out all of the air space, restricts the arc path, and cools the conducting gases.

A further object is to provide a pull chain socket switch of the above nature which will be capable of safely carrying and interrupting a current three to four times as great as was possible with the former air-break type of socket switch using the same size of metal contacts.

A further object is to provide a device of the above nature which will be simple in construction, having only a fraction of the number of parts as compared with the previous standard type of sockets of this general nature.

A further object is to provide a pull chain socket of the above nature which will be inexpensive to manufacture, compact, ornamental in appearance, and very efficient and durable in use.

With these and other objects in view there has been illustrated on the accompanying drawings one form in which the invention may be conveniently embodied in practice.

In the drawings:

Fig. 1 represents a vertical sectional view, partially broken away, of the electric pull chain socket switch.

Fig. 2 is a fragmentary sectional view of the same, taken along the line 2—2 of Fig. 1, the switch being shown with the circuit closed.

Fig. 3 is a top plan view looking downward upon Fig. 2.

Fig. 4 is a transverse sectional view, taken along the line 4—4 of Fig. 1, looking downwardly.

Fig. 5 is a transverse sectional view taken along the line 5—5 of Fig. 1, looking upwardly.

Fig. 6 is a perspective view in separated relation of the insulating cap, the movable contact carrier, the spring-operated ratchet and associated parts.

Fig. 7 is a top plan view of the rotary contact carrier.

Fig. 8 is a perspective view of one of the stationary contact members which is formed integrally with the center contact of the screw shell socket.

Fig. 9 is a perspective view of the other stationary contact member.

Fig. 10 is a perspective view of one of the pairs of cap-supporting conducting brackets.

Fig. 11 is a bottom view of the insulating base member.

Fig. 12 is a top plan view of the same.

Fig. 13 is a perspective view of the same.

Fig. 14 is a diagrammatic development view of the cooperating contacts with the rotary contact member shown in "on" position.

Fig. 15 is a similar view with the rotary contact advancing to "off" position.

Fig. 16 is a similar view with the rotary contact in "off" position.

An arc, as generally understood, consists of a stream of charged particles passing through an open space in the form of a tube or core surrounded by luminous gas. The arc continues to carry current as long as the central portion remains hot enough to maintain the flow of charged particles. It can be ruptured and destroyed by stretching it, cooling it, or obstructing it. In the present improved form of pull chain socket, the arc is immediately checked by interposing an insulating cooling barrier between the interrupted contacts, whereby it will be completely smothered and extinguished. The obliteration of the arc is partly due to the fact that the open spaces about the contacts are completely obliterated. Under these conditions, the arc is immediately cooled and choked off and simply cannot exist as there is nothing to support the conducting stream of charged particles forming the arc.

Referring now to the drawings in which like reference numerals denote corresponding parts throughout the several views, the numeral 10 indicates a stationary contact-carrying insulating

base member which is substantially cylindrical in shape and preferably formed of porcelain. The base member 10 is provided with a central socket 11 extending downwardly into its upper face 11a and within which is mounted the lower end of a cylindrical pin 12 extending upwardly and terminating in an upper square head 13 having a slot 14. By means of this construction the pin may be adjusted whenever desired. The head 13 of the pin 12 is seated within a square socket 13a in an upper insulating cap member 15 also formed of porcelain and having a cylindrical opening 16 at its center for permitting a screw driver to be readily inserted in the slot 14 of the head 13. The head 13 may thus be depressed below the socket 13a and twisted 90 degrees within a cylindrical chamber 16a in either direction for adjusting the tension of a coiled spring 17 surrounding the pin 12.

20 The coiled spring 17 has a vertical upper extremity 18 seated in an aperture 19 in the head 13, the lower extremity of said spring 17 being horizontal and connected with an upstanding lug 20 of a ratchet 21. The ratchet 21 is adapted to lie in flat contact with the top of a rotary contact carrier 22, preferably formed of a "phenol condensation product" or other similar insulating material. The ratchet 21 is provided with an enlarged upper inclined radial wing 23 for 25 guiding a switch-operating bead chain 24, the inner extremity of which is detachably locked within a slotted eye 25 depending from one side of said wing 23.

30 The bead chain 24 is also guided by the outer circular periphery 24a of the rotary contact carrier 22, from which it passes tangentially at a slight upward incline through a flared tubular outlet bracket 26 having its lower end seated in a slot 26a of the stationary base 10. The bracket 26 passes outwardly through an outer enclosing metallic shell 27 within which is an insulating lining 28, as clearly shown in Figs. 1 and 4.

35 The ratchet member 21 is provided with four downwardly inclined lugs 29 adapted to engage in a similar number of inclined sockets 30 provided in the top surface of the rotary contact carrier 22, as shown in Fig. 7. The ratchet 21 is adapted to index said carrier 22 one quarter 40 of a circumference with each actuation of the pull socket chain 24.

45 The spring 17 is arranged to press the rotary contact carrier 22 downwardly upon the stationary base member 10 at all times and is also adapted to return said carrier to its initial position after each operation of the switch. The rotary contact carrier 22 is provided on its under face with a central socket 31 partially enclosed by a pair of curved opposed ribs 22a for receiving 50 the central portion of the contact member 36 and adapted to fit over an annular boss 32 in the stationary base 10 surrounding the socket 11. The socket 31 has a central aperture 33 for permitting said carrier 22 to rotate freely and 55 slide up and down upon the pin 12. The ribs 22a serve as additional barriers to prevent arcing between the central portion of said rotary contact 36 and the stationary contacts 43 and 44.

60 Extending downwardly from the rotary carrier 22 are a pair of curved inclined lugs 34 and 35 which are adapted to form supports for a two-part integral contact member 36 having inclined outer extremities 37 and 38 adapted to lie loosely in engagement with the inclined lugs 34 and 35.

65 70 75 The contact member 36 is provided with a pair

of upturned lugs 38a for fitting into slots 38b at the base of the lugs 34 and 35, whereby said movable contact member 36 will be caused to move with said rotary carrier 22. Surrounding the boss 32 is an annular depressed socket 10a having its base provided with a plurality of raised inclined serrations, similar to a face ratchet, and providing four connected abrupt shoulders 40 and cam sections 41 and 42. The lugs 34 and 35 have abrupt shoulders 39 at their outer extremities which are adapted to abut tightly against similar abrupt shoulders 40 of the four equally spaced serrations described above, when the switch is in the "on" and "off" positions.

15 The two opposed inclined sections 41 are left blank so as to form insulating seats for the movable contact extremities 37 and 38 when the switch is in the "off" position, while the other two inclined sections 42 are provided with inclined stationary contacts 43 and 44 for engaging the extremities of the movable contact 36 when the switch is in the "on" position. By means of this construction, it will be seen that positive insulating barriers are interposed between and around each set of movable and stationary contacts, eliminating all air space which might support an arc and instantly cooling and breaking any arcs which may initially form at the interruption of the circuit.

20 The contact 43 leads directly to one of the line conductors through an angular supporting bracket 45 connected to the base 11 as by a screw 46 and having a lateral binding post 47 located near the upper end thereof. The bracket 45 is also provided at its top with a horizontal eye lug 48 for receiving a screw 49 extending down through the upper insulating cap 15. The bracket 45 has a base 50 provided with a tapped hole 51 to receive a screw 46 which passes 25 through a lateral aperture 51b of the stationary contact 43, thus securely fastening said contact 43 and bracket 45 to the base 10.

30 A similar supporting bracket member 52 is connected at its lower end to a screw shell 52a 45 by means of a conducting screw 53, and has an upper eye lug 54 similar to the eye lug 48 for receiving a screw 55 for connection with the base 10. The bracket 52 also has a binding post 56 similar to the binding post 47.

35 Current is supplied to the switch through a suitable twin-wire conductor cord 57, which is adapted to pass through an upper metallic shell 58 and comprises a pair of insulated wires 59 and 60 which are connected to the two binding posts 55 47 and 56, respectively.

40 The stationary contact 44 is provided with an integral inwardly-extending resilient tongue 61 forming the central contact of the socket, said tongue 61 being adapted to cooperate with the 45 center terminal of a lamp 61a or other current consuming or conveying device which may be driven into the screw shell 52a.

45 The stationary contact 44 is connected to the tongue 61 by a depending integral strip 62 passing through an aperture 63 in the base 10, said strip 62 being attached to the underside of said base 10 by a screw 64 and nut 65. The tongue 61 is adapted to be pressed upwardly against the bottom surface of the insulating base 10 by 50 the lamp 61a and is shielded against flashing-over upon the upper inturned part 66 of the screw shell 52a by a downwardly-extending U-shaped rib 67 formed integral with said base 10 and surrounding the sides of said tongue 61.

Operation

In operation, assuming the switch to be in the closed position, when the switch-actuating bead chain 24 is pulled, the rotary carrier 22 will rise on the inclined stationary contact members 43 and 44 in the sockets 42 of the base 11, causing the two extremities 37 and 38 of the movable contact 36 to ride off the upper ends of the stationary contacts 43 and 44. The compressive force of the spring 17 will then come into action, causing the carrier 22 to snap down suddenly, bringing the movable contact extremities 37 and 38 into the inclined sockets 41. The shoulders 39 and 40 will then lie in abutment with each other and the rim of the carrier 22 will lie flat upon the upper surface of the base 11. All open spaces will thus be filled, causing any arcs which may have started to flow between the contacts, to be instantly lengthened, cooled and extinguished.

When the chain is released, the ratchet 21 will be restored by the torsional action of the spring 17 to its initial position, ready for again snapping on the switch.

One advantage of the present invention lies in the fact that when the tension in the chain 24 is released, there is no danger of having the same come into contact with "live" parts of the switch, because all such parts are completely enclosed by insulating barriers as described above.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric switch of the rotary type, an insulating stationary base having an annular depressed groove formed in the face thereof, a plurality of abrupt shouldered inclined recesses in said groove, stationary contact members arranged in alternate recesses, a rotatable contactor member having inclined arms to intermittently pass over said stationary contact members, an insulating carrier for supporting said contactor member and having telescoping relationship with said base, said carrier having a plurality of abrupt shouldered inclined cams adapted to support said arms and fit against said recesses, said carrier having a rim outside of said cams for engaging the surface of said base in overlapping relationship, and means for rotating said carrier, the telescoping arrangement of said carrier and base and the interfitting of said cams in said recesses serving to obliterate the open air space and prevent the formation of arcs.

2. In an electric switch of the rotary type, an insulating stationary base having an annular depressed groove formed in the face thereof, a plurality of abrupt shouldered inclined recesses in said groove, stationary contact members arranged in alternate recesses, a rotatable contactor member having inclined arms to intermittently pass over said stationary contact members, an insulating carrier for supporting said contactor member and having telescoping relationship with said base, said carrier having a

plurality of abrupt shouldered inclined cams adapted to support said arms and fit against said recesses, said carrier having a depending annular flange forming a barrier to prevent arcing between the central part of said rotatable contact member and said stationary contacts, and means for rotating said carrier, the telescoping arrangement of said carrier and base and the interfitting of said cams in said recesses serving to obliterate the open air space and prevent the formation of arcs.

3. In an electric switch of the rotary type, an insulating stationary base having an annular depressed groove formed in the upper face thereof, the base of said groove having a plurality of ratchet depressions, stationary contacts seated in alternate depressions, an insulating rotary carrier member having a plurality of depending abrupt shouldered cams shaped to fit said ratchet depressions, said carrier having a rim extending outwardly beyond said cams for engaging the surface of said base, a bridging member having a pair of contact arms supported on the cams of said carrier, and means depending from said carrier inside of said cams for interposing an arc barrier between said movable and stationary contacts.

4. In an electric switch of the rotary type, an insulating stationary base having an annular depressed groove formed in the upper face thereof, the base of said groove having a plurality of ratchet depressions, stationary contacts seated in alternate depressions, an insulating rotary carrier member having a plurality of depending abrupt shouldered cams shaped to fit said ratchet depressions, said carrier having a rim extending outwardly beyond said cams for engaging the surface of said base, and completely covering said groove, a bridging member having a pair of contact arms supported on the cams of said carrier, and means depending from said carrier inside of said cams for interposing an arc barrier between said movable and stationary contacts.

5. In an electric switch of the rotary type, an insulating stationary base having an annular depressed groove formed in the upper face thereof, the base of said groove having a plurality of inclined ratchet depressions, stationary contacts seated in alternate depressions, an insulating rotary carrier member having a plurality of depending abrupt shouldered inclined cams shaped to fit said ratchet depressions, said carrier having a rim extending outwardly beyond said cams for engaging the surface of said base, a bridging member having a pair of contact arms supported on the cams of said carrier, and means depending from said carrier inside of said cams for interposing an arc barrier between said movable and stationary contacts.

6. In an electric switch of the rotary type, an insulating stationary base having an annular depressed groove formed in the upper face thereof, the base of said groove having a plurality of ratchet depressions, stationary contacts seated in alternate depressions, an insulating rotary carrier member having a plurality of depending abrupt shouldered cams shaped to fit said ratchet depressions, said carrier having a rim extending outwardly beyond said cams for engaging the surface of said base, a bridging member having a pair of contact arms supported on the cams of said carrier, means depending from said carrier inside of said cams for interposing an arc barrier between said movable and stationary contacts, and a

ratchet member having toothed engagement with said carrier for rotating the same.

7. In an electric switch for a light socket, an insulating base having a centrally depressed annular recess, the base of said recess having a plurality of inclined cams located therein, said cams having abrupt shoulders, stationary contacts resting on alternate cams, a rotatably insulating carrier having face engagement on its periphery with the rim of said annular recess, said carrier having cam projections having abrupt shoulders projecting down into said annular recess, contact members on alternate cam projections for cooperating with said stationary base contacts, and ratchet means connected to said carrier for operating the same.

8. In an electric switch of the rotary type, an insulating stationary base having an annular depressed groove formed in the upper face thereof, the base of said groove having a plurality of ratchet depressions, stationary contacts seated in alternate depressions, an insulating rotary downwardly spring-pressed carrier member having a plurality of depending abrupt shouldered cams shaped to fit said ratchet depressions, said carrier having a rim extending outwardly beyond said cams for engaging the surface of said base, a bridging member having a pair of contact arms supported on the cams of said carrier, and means depending from said carrier inside of said cams for interposing an arc barrier between said movable and stationary contacts.

9. In an electric pull chain socket switch, an insulating base having a plurality of inclined cam recesses formed therein, alternate recesses being provided with stationary contact members, a rotary contact member having a pair of connected

inclined contact extremities adapted to bridge said stationary contact members, and an insulating carrier for indexing said rotary contact member, said carrier having a rim located in flat surface engagement with said base.

10. In an electric pull chain socket switch, an insulating base having a plurality of spaced shouldered circumferential cam depressions formed therein, said depressions having end shoulders, inclined contact members being arranged in alternate depressions of said base, a rotary contact member having a pair of connected inclined contact extremities adapted to intermittently engage said stationary contact members, and an insulating carrier for said rotary contact member telescoping with said base having shoulders for engaging the shoulders of said depressions to obliterate the air space and form barriers for preventing the formation of arcs, said carrier having a rim for engaging the surface of said base.

11. In an electric switch, a rotary contact member having a pair of connected inclined contact terminals, an insulating carrier having a pair of inclined shouldered backing-up cam lugs for supporting said terminals, and insulating base member having a plurality of spaced inclined shouldered recesses, stationary contacts located in alternate recesses of said base member for cooperating with said rotary terminals, means for indexing said carrier, and spring means for forcing said carrier into telescoping engagement with said base member when the switch is in fully opened or fully closed position to prevent arcing, said carrier having a pair of depending curved ribs located inside of said backing-up lugs to form additional barriers against arcing.

HARMON J. COOK.
